UNITED STATES PATENT OFFICE

2,184,481

AIR CONDITIONING APPARATUS

William Henry Aubrey, Waynesboro, Pa., assignor to Frick Company, Waynesboro, Pa., a corporation of Pennsylvania

Application July 2, 1938, Serial No. 217,252

7 Claims. (Cl. 62—129)

This invention relates to air conditioning and more particularly to an air conditioning unit which permits of simple installation and is adapted to condition the air within an enclosure. 5 Prior to the instant invention, room cooling units have been designed which, while they function to condition air to a more or less desirable degree are unsatisfactory for various reasons. For example, room cooling units of the 10 type which were of the size comparable with the ordinary heating radiator have been found to be of insufficient capacity to properly condition enclosures having appreciable heat loads imposed thereon. Similar units but of larger capacity, 15 which while they take care of the heat load, are undesirable because of the large amount of floor space that is necessary to be allocated for their installation, which floor space is needed for other purposes. A further disadvantage of prior conditioners of the size comparable to an appreciable 20 heat load lies in their appearance which is unsightly in a modern business office for example. Another disadvantage attributed to air conditioners of the type which are designed to rest on the floor of the room to be conditioned and 25 against a wall thereof, is the fact that they occupy a wall area which could be better utilized, from a business point of view, by the location in their place of filing cabinets and the like. 30 It is an object of my invention to provide an air conditioned unit of the package type of relatively simple design which will operate efficiently and effectively in enclosures having appreciable heat loads therein.

35 It is a further object of my invention to provide a compact package type of air conditioning unit which permits of installation near the ceiling of the space to be conditioned, thereby occupying no usable floor space and wall area. 40 Other objects and the nature and advantages of the invention will be apparent from the following description taken in conjunction with the accompanying drawing, wherein:

Fig. 1 is a sectional view taken along a horizontal plane 1—1 of Fig. 3 close to the top of the unit;

Fig. 2 is a vertical section taken along the line 2—2 of Fig. 3;

Fig. 3 is a vertical section taken along the line 50 3—3 of Fig. 1; and,

Fig. 4 is a view in perspective illustrating the unit installed in a room to be conditioned.

Referring to the drawing, the unit casing 10 which is preferably of sheet metal may be lined 55 with sound deadening material 11, whereby the

operation of the air conditioning unit may take place with the transmission of a minimum of noise to the enclosure in which the unit is installed. In order to separate the refrigerant translating equipment from the low side or evaporating unit wherein the air to be conditioned is conducted in heat exchange relation with said evaporating unit, as will later be explained, the partitions 12 are incorporated in the construction of the unit as illustrated and may 10 be lined with heat insulating material 13.

Within the machinery compartment 14 may be located an electric motor 15 for operating the compressor 16 through the medium of belt drive 17. Compressed refrigerant will be passed 15 through the pipe 18 to the condenser 19 which is preferably water cooled, though an air cooled condenser may be utilized. Here the compressed gaseous refrigerant will be liquefied and fed to the evaporator 20 through the pipe 21 and expansion device 22. Vaporized refrigerant evolved in the said evaporator will be returned to the compressor 16 by means of pipe 23 and the cycle repeated. To effectively remove heat from the condenser 19, water conduits 24 and 25 20 may be associated therewith, the conduit 24 being connected to the city water system or other convenient source such as a well or the like and the conduit 25 associated with the city sewer system or other convenient waste water system. 30 If desired, the compressor 16 may likewise be water cooled.

The compartment 26 within which the evaporator 20 is located is formed with openings 27 and 28, one of which may be optionally used 35 as the intake for the air to be conditioned. For example, as illustrated, the openings 28 are closed by the cover plates 29 and the opening 27 has positioned therein the filter 30, whereby air will be taken in through the opening 27, filtered and drawn over the evaporator 20 by the fan 31 driven by a second motor 32 through the medium of the belt drive 33. When installation conditions are such that an air inlet at one of the openings 28 is more convenient than the one at 40 27 and is better for some reason, the cover plate 29 may be associated with the opening 27 and the filter 30 associated with one of the openings at 28.

One of the openings 28 are adapted to be 50 associated by a duct not shown with the atmosphere whereby fresh air as well as air from the enclosure to be conditioned may be passed through the conditioning unit.

Not only may air be drawn through the open- 55

ing 27 into the fan 31 but, when desired, air may be drawn from the room to be conditioned at a relatively high temperature through one of the openings 35 in the casing 10 within which may also be positioned a filter 36 and a damper D, whereby the relative proportions of air taken into the unit can be controlled. This air will be drawn about the lower portion of the casing of the fan 31 and underneath the partition 37 to join the relatively cool air just passed over the evaporator 20 and be sucked through the fan 31 and discharged through the outlet opening 38 of the plenum chamber 39. Optional openings 40 associated with the chamber 39 are covered by the closures 41, one of which when desired may be associated with the opening 38 and the conditioned air discharged through one of the openings 40.

In order to insure the proper functioning of the elements of the mechanism located within the compartment 14, arrangement has been provided to effect the cooling of the said elements, said arrangement comprising a fan or blower 42 driven by the motor 32 which also drives the main fan or blower 31. The fan 42 is arranged to draw in air from the conditioned enclosure or from the atmosphere through the opening 43 or optionally the opening 44 as desired, depending upon which opening the cover plate 45 is associated with. The air is drawn into the chamber 46 by the small fan or blower 42, and discharged through the duct 47 and into the compartment 14 to cool the elements therein. Though either of the cover plates 48 and 49 may be removed from the openings 50 and 51 to permit the discharge of air from the compartment 14 back into the enclosure, it is preferred that the air be discharged through the duct 52 to the atmosphere outside of the conditioned enclosure in order that the heat generated by the mechanism within the machinery compartment be more or less removed.

In order to provide means for reheating the conditioned air, in addition to the arrangement whereby recirculated air entering at 35 may be mixed with cooled air, the heating coils 53 may be located adjacent the evaporator 20 to properly temper the air during its passage through the conditioning unit. Further, in addition to this function for the heating coils 53, they may also serve for heating during the winter season at which time the refrigeration system may or may not be in operation.

With the conditioning unit installed in an enclosure to be conditioned, the operation of the fan or blower 31 will cause air from the enclosure to be conditioned to be taken in through the opening 27 and filter 30 into the chamber 26 through the cooling coils 20, and further through the heating coils 53 which may or may not be in operation to affect the relative humidity or for other purposes. If further change of relative humidity is desired, a quantity of air may be taken directly to the fan or blower 31 from the conditioned space through the opening 35 and filter 36. The air thus taken into the conditioning unit is discharged by the fan or blower 31 into the chamber 39 which is lined with sound absorbing material 11 and discharged outwardly through the opening 38 back into the enclosure to be conditioned. To further reduce objectionable noises the plenum chamber 39 has been arranged to effectively reduce the velocity of the air through the outlet openings as compared with the

fan discharge velocity, whereby the noise is more or less effectively eliminated.

When no refrigeration or heating is desired, the fan or blower 31 may be operated, though the coils 20 and 53 have no circulation of cooling and heating medium, respectively, therethrough, and the enclosure may simply be ventilated and the air therein cleaned by passage through the filters of the unit. In accordance with weather requirements, the refrigeration system may be placed in operation to condition the air with regard to temperature. Similarly, the heating coils may be placed in operation to heat the air of the enclosure to be conditioned at times when the refrigeration system is not in operation. Simple starting and stopping controls, common in the art, may be utilized to effect the operation described, or automatic controls comprising thermostats, pressure-stats, humidostats, and their equivalents may function to serve this purpose automatically.

The small blower 42 operates to properly ventilate the machine compartment 14 by taking air from the enclosure to be conditioned and passing it through the said compartment 14 and out to the atmosphere external of the enclosure to be conditioned, whereby smoke and vitiated air is simultaneously removed from the conditioned enclosure and the low heat level of such air is utilized to cool mechanism within the compartment 14 which is at a relatively high level before it is disposed of.

Though the air conditioning unit is preferably suspended from the ceiling or supported close to the ceiling of the conditioned space above the heads of the occupants, it is conceivable that a conditioning unit in accordance with my invention may be located in other places in a room or enclosure. However, when the unit is suspended from the ceiling, it is significant that no usable floor space or wall area is wasted and its location in relatively different places directly beneath the ceiling will not affect the proper operation of the device for any of the air outlet and air inlet openings may be optionally utilized by the proper placing of the cover plates as described. Further, though the unit may function sans ducts for the air to be conditioned and the conditioned air, versatility is claimed for the device for it readily lends itself for adaptation to installations incorporating ducts whereby a more positive and superior distribution of the conditioned air may be effected. This is especially desirable, for example, in certain situations wherein it is necessary to lead portions of the conditioned air to the space which may be more or less remote to a main enclosure to be conditioned.

While I have described the air conditioning unit as preferably suspended from the ceiling and my invention is directed to providing a unit of such dimensions and of such arrangement as to make this practical, it is obvious that the unit may be placed in any desired location. For example, it may be placed in the basement below the space to be conditioned with ducts leading to the conditioned space. In that case it may be desirable to suspend the unit from the basement ceiling and avoid the use of floor space in the said basement. On the other hand, it may be desirable to place the unit on the floor of the conditioned space, arranging the top air outlet connection so as to blow the conditioned air toward the ceiling. In that case shelving, counters, etc., can be placed over the top of the unit making provision, however, that the discharge opening be

left exposed. Since the unit is relatively low, there will be a great deal of usable space above it.

It will be obvious to those skilled in the art that various changes may be made in this device without departing from the spirit of the invention and therefore the invention is not limited to what is shown in the drawing and described in the specification but only as indicated in the appended claims.

10 I claim:

1. An air conditioning unit comprising a casing, said casing including a machinery compartment and a conditioning compartment, both said compartments arranged in substantially the same

15 horizontal plane, said conditioning compartment being substantially L-shaped and comprising an air tempering section and a plenum chamber, said section being located in one leg of said L and said chamber located in the other leg, a refrigerant condensing apparatus in said machinery compartment, an air tempering apparatus in said tempering section of said conditioning compartment, means for disposing of heat generated in said machinery compartment, and means for

20 passing air through said conditioning compartment comprising air moving means located at the junction of said tempering section and said plenum chamber, said air moving means arranged to take in air in one direction and discharge air in a direction at an angle to said first direction.

25 2. An air conditioning unit comprising a relatively low, relatively long, relatively wide casing, said casing including a machinery compartment and a conditioning compartment, means for insulating the two compartments from each other, said compartments being arranged in substantially the same horizontal plane, said conditioning compartment comprising an air tempering section and a plenum chamber, said section and said chamber being angularly disposed, fan means located at the junction of the section and the chamber, said fan means being constructed to take air in one direction and discharge it at an angle to said direction.

30 3. An air conditioning unit comprising a relatively low, relatively long, relatively wide casing, said casing including a machinery compartment and a conditioning compartment, means for insulating the two compartments from each other, said compartments being arranged in substantially the same horizontal plane, said conditioning compartment comprising an air tempering section and a plenum chamber, said section and said chamber being angularly disposed, fan means located at the junction of the section and the chamber, said fan means being constructed to take in air in one direction and discharge it at an angle to said direction, refrigerating elements of measurable weight disposed in said machinery compartment and said conditioning com-

partment in weight transmitting relationship to said unit, and means for suspending said unit within a room or space to be cooled from a ceiling or top wall thereof with a major plane of the relatively long, relatively wide casing generally parallel to said ceiling or top wall.

5 4. An air conditioning unit comprising a relatively low, relatively long, relatively wide casing, said casing including a machinery compartment and a conditioning compartment, said machinery compartment being substantially entirely insulated, means for ventilating said machinery compartment, said compartments being arranged in substantially the same horizontal plane, said conditioning compartment comprising an air tempering section and a plenum chamber, said section and said chamber being angularly disposed, fan means located at the junction of the section and the chamber, said fan means being constructed to take in air in one direction and discharge it at an angle to said direction.

10 5. An air conditioning unit comprising a relatively low, relatively long, relatively wide casing, said casing including a machinery compartment generally rectangular in a horizontal plane and a conditioning compartment generally L-shaped in a horizontal plane, said compartments being arranged in substantially the same horizontal plane, said rectangular machinery compartment and said conditioning compartment being of a size to cooperate with each other and comprise the said conditioning unit which is generally rectangular in horizontal section, said conditioning compartment comprising an air tempering section and a plenum chamber, a cooling element in said section and a fan associated with said section and said plenum chamber in a manner to suck air over said cooling element and to discharge same into said plenum chamber.

15 6. The structure recited in claim 5, said machinery compartment being entirely insulated and means for ventilating said machinery.

20 7. An air conditioning unit comprising a relatively low, relatively long, relatively wide casing, said casing including a machinery compartment and a conditioning compartment, said machinery compartment being generally rectangular in horizontal section, said conditioning compartment being generally L-shaped in horizontal section, means for insulating the two compartments from each other, said machinery compartment and said conditioning compartment cooperating to comprise said air conditioning unit which is of general rectangular horizontal section, refrigerant translating apparatus in said machinery compartment, cooling means and air moving means located in said conditioning compartment, said air moving means cooperating with said L-shaped conditioning compartment to effect angular change of air movement therethrough.

25 35 40 45 50 55 60 WILLIAM HENRY AUBREY.
